UNITED STATES PATENT OFFICE.

JAMES R. MANSFIELD, OF ALEXANDRIA, VIRGINIA.

TRADE-MARK FOR A BADGE, PIN, OR FRATERNAL EMBLEM.

45,598.

Specification for Design.

Patented Apr. 14, 1914.

Application filed January 14, 1913. Serial No. 742,060. Term of patent 7 years.

To all whom it may concern:

Be it known that I, JAMES R. MANSFIELD, a citizen of the United States, residing at Alexandria, county of Alexandria, State of Virginia, have invented a new, original, and ornamental Design for Badges, Pins, and Fraternal Emblems, of which the following is a specification, reference being had to the accompanying drawing, forming part thereof.

As shown in the drawings the design consists of a shield shaped figure having a border of stars inclosing a shield shaped field having in its upper half the representation of a square above the letter V, and in its left hand lower quarter the representation of a compass above the letter L; and in its right hand lower quarter the representation of an arm and hammer above the letter P. The upper half of the field being white, and the lower hand quarter being blue, and the lower right hand quarter being red.

I claim:

The ornamental design for a badge, pin, or fraternal emblem, as shown and described.

JAMES R. MANSFIELD.

In presence of:—

ANNA E. MANSFIELD,
GEO. M. COPENHAVER.
